DRYING APPARATUS

Milton E. Hanson, Haddonfield, N. J., assignor to
B. F. Sturtevant Company, Boston, Mass.

Application February 2, 1940, Serial No. 316,898

2 Claims. (Cl. 34—160)

This invention relates to drying apparatus and relates more particularly to dryers using heated air for drying web material such as paper, cloth, and the like or for the drying of printing or coatings on the surface of same.

This invention provides a compact, efficient dryer providing the air heater and a centrifugal fan for moving air over same, inside a single insulating casing which also houses drying nozzles and recirculated air passages. This design of dryer has been found particularly suitable for use with small paper printing machines, the space required being much less than required by prior dryers having fans and heaters mounted on the exterior of the dryer casings.

An object of the invention is to increase the efficiency of, and to reduce the space required by, web dryers.

Other objects of the invention will be apparent from the following description and from the drawing.

The invention will now be described with reference to the drawing, of which:

Fig. 1 is a side elevation, with a portion in section and a portion in dotted outline, of one embodiment of a dryer according to this invention;

Fig. 2 is a sectional view along the lines 2—2 of Fig. 1, and

Fig. 3 is an enlarged section along the lines 3—3 of Fig. 2.

The dryer unit 5 has the heat insulating casing 6 completely enclosing same. Mounted centrally in one end of the unit is the centrifugal fan 7 with the two oppositely disposed axial inlets 8. The outlet 9 of the fan is connected to the two upper diverging walls 10 and 11 which extend to the ends of the unit, and to the side walls 11, which walls form a diverging air plenum chamber 12.

The dryer nozzles 13 extend horizontally crosswise the lower end of the chamber 12 and discharge air downwardly upon the moving web 14 which it is the purpose to dry. The finned heater tubes 15 extend crosswise the chamber 12 just above the nozzles 13, and are adapted to be supplied with steam for heating the air blown by the fan 7 through the nozzles 13.

The plates 16 extend vertically between adjacent nozzles 13 to points adjacent the web 14 and perform the functions of scraping off the film of air which tends to adhere to the web 14 and to leave the dryer with same; of providing turbulence in air flow thus expediting the drying action, and of equalizing the drying effect

of the air by guiding it crosswise the web so that no one part dries before another, all of which result in adding to the efficiency and compactness of the dryer by cutting down air and heat losses and decreasing the number of nozzles required.

The air from the nozzles 13 after leaving the web, is recirculated from both transverse sides of the web into the two fan inlets 8 as indicated by the arrows indicating air flow, of Fig. 2.

Fresh make-up air enters from outdoors through the inlet 18, and equal volumes of the recirculated air are exhausted through the outlet 19.

15 The auxiliary fresh air inlet openings 20 are provided in the lower casing 21 and communicate with the lower side of the web 13 as it enters the dryer, and are for the purpose of ventilating the lower surface of the wet web adjacent the fountains and impression rolls for preventing dangerous fumes from accumulating.

In operation, the fan draws outdoor air through the inlet 18, and recirculated air through the space between the walls of the plenum chamber 12, the walls 6, and the fan casing, into the inlets 8, and forces the mixed fresh and recirculated air through the plenum chamber 12, over the heater tubes 15, and through the nozzles 13 upon the surface of the web 14. Exhaust air flows through the outlet 19 into the atmosphere.

25 While one embodiment of the invention has been described for the purpose of illustration, it should be understood that the invention is not limited to the exact apparatus and arrangement 30 of apparatus illustrated as changes therefrom may be made by those skilled in the art without departure from the essence of the invention.

35 What is claimed is:

1. A dryer for web material comprising a casing having an inlet for fresh air, an outlet for moist air, and means for moving a web to be dried therethrough; comprising a plurality of aligned air nozzles spaced longitudinally of said casing and extending substantially the full length thereof; each nozzle extending a substantial distance cross-wise said casing so as to project air over the entire surface of a web moving therethrough; an air heater extending cross-wise said casing above and substantially in alignment with said nozzles; a centrifugal fan above said heater and nozzles, said fan having axial inlets at opposite side walls of said casing and having a downwardly directed outlet, and means including diverging walls forming a plenum chamber connecting said outlet of said fan with

opposite end walls of said casing, said plenum chamber having side walls spaced substantial distances from said side walls of said casing and forming passages for the air recirculated from said nozzles to said inlets of said fan, said heater extending substantially completely across the outlet of said chamber.

2. A dryer for web material comprising a casing having an inlet for fresh air, an outlet for moist air, and means for moving a web to be dried therethrough; comprising a plurality of aligned air nozzles spaced longitudinally of said casing and extending substantially the full length thereof; each nozzle extending a substantial distance cross-wise said casing so as to project air over the entire surface of a web moving therethrough; an air heater extending cross-wise and lengthwise said casing above and substantially in alignment with said nozzles; a centrifugal fan at one end of said casing above 20

said heater and nozzles, said fan having axial inlets at opposite side walls of said casing and having a downwardly directed outlet; means including diverging walls forming a plenum chamber connecting said outlet of said fan with opposite end walls of said casing, said plenum chamber having side walls spaced substantial distances from said side walls of said casing and forming passages for the air recirculated from 5 said nozzles to said inlets of said fan, said heater and said nozzles extending substantially completely across the outlet of said chamber, and means forming partitions between adjacent nozzles and extending below same and connecting with said passages for scraping off the film 10 of air tending to leave the dryer with the web being dried, and for guiding the air from said nozzles with the air scraped off said web, into 15 said passages for recirculation.

MILTON E. HANSON.
